Primary Examiner — Mehri F Bajoul(74) *Attorney, Agent, or Firm* — Parsons Behle & Latimer(57) **CLAIM**

The ornamental design for a soccer goal, as shown.

DESCRIPTION

FIG. 1 is a perspective view showing the soccer goal embodying the new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof; and,

FIG. 7 is a bottom plan view thereof.
